(57) **ABSTRACT**

A new *Pelargonium* plant named 'PECZ0011' particularly distinguished by the bright red colored and round inflorescences with striking bicolor white and red florets held above the dark-green foliage, very heat and drought tolerant.

1 Drawing Sheet

1

Latin name of the genus and species of the plant claimed:
Pelargonium x hortorum.

Varietal denomination: 'PECZ0011'.

BACKGROUND OF THE NEW PLANT

The present invention comprises a new *Pelargonium*, botanically known as *Pelargonium x hortorum*, and herein-after referred to by the variety name 'PECZ0011'.

'PECZ0011' is a product of a planned breeding program. The new cultivar 'PECZ0011' has bright red colored inflorescences held above the dark-green foliage, with single-flowering florets with a striking white centre.

'PECZ0011' originates from a hybridization in a controlled breeding program made in April 2012, in a greenhouse in Enkhuizen, The Netherlands. The female parent was an unpatented, proprietary plant of *Pelargonium x hortorum* parentage, identified as '11021-1' with pink single florets and larger and more open plant habit when compared to 'PECZ0011'.

The male parent of 'PECZ0011' was an unpatented, proprietary plant of *Pelargonium x hortorum* parentage, identified as 'k09-5562-2' with more orange red colored florets and a more compact plant habit when compared to 'PECZ0011'. The resultant seed was sown in December 2012.

'PECZ0011' was selected as one flowering plant within the progeny of the stated cross in April 2012 in a greenhouse in Enkhuizen, The Netherlands.

The first act of asexual reproduction of 'PECZ0011' was accomplished when vegetative cuttings were propagated from the initial selection in May 2012 in a greenhouse in Enkhuizen, The Netherlands.

2

BRIEF SUMMARY OF INVENTION

Horticultural examination of plants grown from cuttings of the plant initiated in May 2012 in Enkhuizen, The Netherlands, and continuing thereafter, has demonstrated that the combination of characteristics as herein disclosed for 'PECZ0011' are firmly fixed and are retained through successive generations of asexual reproduction.

'PECZ0011' has not been observed under all possible environmental conditions. The phenotype may vary significantly with variations in environment such as temperature, light intensity, and day length.

Plant Breeder's Rights for this cultivar were applied for in the European Union on Sep. 27, 2016, No. 2016/2336 and in Canada on Apr. 7, 2017, No. 17-9175. 'PECZ0011' has not been made publicly available prior to the effective filing date of this application, notwithstanding any disclosure that may have been made less than one year prior to the effective filing date of this application by the inventor or another who obtained 'PECZ0011' directly from the inventor.

The following traits have been repeatedly observed and 20 are determined to be the basic characteristics of the new variety. The combination of these characteristics distinguishes this *Pelargonium* as a new and distinct variety.

BRIEF DESCRIPTION OF THE PHOTOGRAPHS

25 The accompanying photographic drawing shows typical flower and foliage characteristics of 'PECZ0011' with colors being as true as possible with an illustration of this type. The photographic drawing shows in FIG. 1, a flowering plant of the new variety and in FIG. 2, a close-up of an inflorescence.

DETAILED BOTANICAL DESCRIPTION

The plant descriptions and measurements were taken in Enkhuizen, The Netherlands in late September 2016 under

natural light. These plants were 18 weeks old and were grown in a 15 cm pot, in a greenhouse trial. From these plants, one plant is shown on the photographs. The photographs were taken in October 2016.

Color references are made to The Royal Horticultural Society Colour Chart (R.H.S.) 2001.

TABLE 1

DIFFERENCES BETWEEN THE NEW VARIETY 'PECZ0011'
AND A MOST SIMILAR VARIETY

	'PECZ0011'	'Stadt bern' (Unpatented variety)
Lower petal color:	Bright red	Bicolor red-pink and pink-white
Stigma color:	Orange-red	White

Plant:

Form, growth and habit.—Upright, rounded growth habit, heat and drought tolerant.

Plant height.—14-17 cm.

Plant height (inflorescence included).—20-24 cm.

Plant width.—12-18 cm.

Roots:

Number of days to initiate roots.—15-18 days at about 22 degrees C.

Number of days to produce a rooted cutting.—21-23 days at 22 degrees C.

Type.—Fine, fibrous, free branching.

Color.—RHS N155B but whiter.

Foliation:

Immature leaf, color upper surface.—Closest to RHS 137C.

Immature leaf, lower surface.—Closest to RHS 137D.

Mature leaf, color upper surface.—Closest to RHS 147A.

Mature leaf, color lower surface.—Closest to RHS 137B.

Length.—6-8 cm.

Width.—7-9 cm.

Shape.—Cordate.

Base shape.—Cordate.

Apex shape.—Acute.

Margin.—Slightly dentate.

Texture upper side.—Hirsute.

Texture lower side.—Hirsute.

Leaf zonation color.—RHS 147A.

Color of veins, upper surface.—144A at base of leaf.

Color of veins, lower surface.—145B at base of leaf.

Pattern of veining.—Palmate.

Petiole color.—RHS 143C.

Petiole length.—6-9.0 cm.

Diameter of petiole.—0.2 cm.

Texture.—Pilose, hirsute, glandular hairs.

Stem:

Quantity of branches.—4.

Color of stem.—Between RHS 145A.

Length of stem.—4-12 cm.

Diameter.—0.4-0.6 cm.

Length of internodes.—0.5-3 cm.

Texture.—Sparsely hirsute, pilose, glandular hairs.

Peduncle:

Color of peduncle.—RHS 147C.

Length of peduncle.—14-19 cm.

Peduncle diameter.—0.3-0.35 cm.

Texture.—Hirsute, glandular hairs.

Pedicel:

Color of pedicel.—RHS 145A.

Length of pedicel.—3-4 cm.

Diameter of pedicel.—0.15-0.2 cm.

Texture.—Sparsely pilose, glandular hairs.

Bud (just before opening):

Color.—Closest to RHS 46B.

Length.—1.5 cm.

Width.—0.3-0.5 cm.

Shape.—Elliptical.

Inflorescence:

Type.—Umbel; semi-spherical or nearly semi-spherical.

Lastingness of individual flowers.—7-9 days at 18° C. temperature.

Number of inflorescences per plant.—4, with 5 immature umbels in various stages.

Fragrance.—None.

Umbel diameter.—9-11 cm.

Umbel depth.—7-8 cm.

Corolla:

Form.—Single.

Number of petals.—5.

Diameter of flower.—About 5.0 cm.

Depth of flower.—1.7-2.2 cm.

Color upper petals, upper surface.—RHS 45B at rim, RHS 66B in middle, RHS 155B at base.

Color upper petals, lower surface.—RHS 52A, with white RHS 155B veins.

Length of upper petals.—2.5 cm.

Width of upper petals.—1.8 cm.

Color lower petals, upper surface.—RHS 45B at rim, RHS 66B at base.

Color lower petals, lower surface.—RHS 52A.

Length of lower petals.—2.5 cm.

Width of lower petals.—2.3 cm.

Petal shape.—Obovate to spatulate.

Apex shape.—Rounded.

Margin.—Entire.

Base.—Attenuate.

Petal texture.—Papillose on both surfaces.

Calyx:

Number of sepals.—5.

Color of sepals.—RHS 144A.

Length of sepals.—1-1.2 cm.

Width of sepals.—0.3-0.4 cm.

Sepal shape.—Lanceolate to linear.

Apex shape.—Acute.

Margins.—Mostly fused.

Texture, upper surface.—Glabrous.

Lower surface.—Glandular hairs, hirsute.

Reproductive organs:

Gynoecium:

Pistil.—1.

Length.—1.2 cm.

Style color.—RHS 145D.

Style length.—0.4-0.5 cm.

Stigma color.—RHS 157C.

Ovary color.—RHS 145A.

Ovary length.—0.4-0.5 cm.

Ovary diameter.—0.2-0.3 cm.

Androecium:

Number of stamens.—7.

Color of filaments.—Whiter than 155D.

US PP29,543 P3

5

Length filaments.—0.4 cm.

Anther color.—RHS 61D.

Length of anthers.—0.2 cm.

Color of pollen.—RHS 169A.

Pollen amount.—Normal.

Fertility/seed set.—Has not been determined to date.

6

Disease/pest resistance.—Has not been determined to date.

What is claimed is:

1. A new and distinct variety of *Pelargonium* plant named
5 'PECZ0011' substantially as illustrated and described
herein.
